UNITED STATES PATENT OFFICE

WILLIAM C. HUFFMAN, OF BROKEN BOW, NEBRASKA

DESIGN FOR A MOTOR VEHICLE SIGNAL

Application filed July 9, 1932. Serial No. 44,289. Term of patent 14 years.

To all whom it may concern:

Be it known that I, WILLIAM C. HUFFMAN, a citizen of the United States, residing at Broken Bow, in the county of Custer and State of Nebraska, have invented a new, original, and ornamental Design for a Motor Vehicle Signal, of which the following is a specification, reference being had to the accompanying drawing, forming part thereof.

Figure 1 is a view in front elevation of a motor vehicle signal;

Figure 2 is a side elevation thereof.

I claim:

The ornamental design for a motor vehicle signal, as shown.

WILLIAM C. HUFFMAN.
